(57) **CLAIM**

The ornamental design for a packaging, as shown and described.

DESCRIPTION

The file of this patent contains at least one drawing executed in color. Copies of this patent or patent application publication with color drawing(s) will be provided by the Office upon request and payment of the necessary fee.

FIG. 1 is a top plan view of a packaging showing a first embodiment of my new design.

FIG. 2 is a bottom plan view thereof.

FIG. 3 is a top plan view of a packaging showing a second embodiment of my new design; and,

FIG. 4 is a bottom plan view thereof.

1 Claim, 2 Drawing Sheets
(1 of 2 Drawing Sheet(s) Filed in Color)

FIG. 1

FIG. 2

FIG. 3

FIG. 4
